T. J. LITTLE, JR

OIL PURIFYING DEVICE

Filed Nov. 11, 1919

FIG. 1.

FIG. 2.

FIG. 3.

UNITED STATES PATENT OFFICE.

THOMAS J. LITTLE, JR., OF DETROIT, MICHIGAN, ASSIGNOR, BY MESNE ASSIGNMENTS,
TO HAROLD H. EMMONS, OF DETROIT, MICHIGAN.

OIL-PUREIFYING DEVICE.

Application filed November 11, 1919. Serial No. 337,139.

- Briefly stated, the objects are, first, to keep the lubricating oil in the crank case free of gasoline and water of condensation which may have passed the pistons, and secondly, to dispose of the vapors distilled from the oil so that the air surrounding the engine will not be filled with objectionable fumes to annoy the operator, if the engine is stationary, and the driver and passengers in the case of a motor car. A further object is to provide a means whereby any vapors which may gather in the crank case of the engine are withdrawn therefrom and disposed of in the same manner, which is preferably by introducing them into the carburetor intake or intake manifold where the partial vacuum, due to the operation of the pistons exercises a sufficient suction to continually withdraw such vapors.
- One embodiment of the present invention will be fully disclosed in the following description, when taken in connection with the accompanying drawing, in which Fig. 1 is a top view of an internal combustion engine, particularly applicable for use in connection with automobiles having my invention incorporated therewith; Fig. 2 is a side view of the same; and Fig. 3 is a longitudinal sectional view through the oil heating element.
- The invention is applicable to all types of internal combustion engines in which a crank case or reservoir for collecting the lubricating oil is provided. In the drawings I have represented the principal portions of a six cylinder automobile engine in which the crank case is indicated at 10, the exhaust manifold at 11, the intake manifold at 12, and the carburetor at 13, this carburetor having an auxiliary air inlet 14. The various other details of the engine are not illustrated, inasmuch as their particular design and construction has no important relation to the details of the present invention.
- Mounted upon the exhaust pipe 11, and preferably integral therewith, as illustrated, is the oil heating element or chamber 15, illustrated in detail in Figure 3. This heating element is shown located at the rear of the cylinders where the exhaust manifold becomes hottest, but it may be located if desired, at any convenient point along the exhaust pipe. This heating element comprises simply a closed chamber having ports in its opposite ends, which serve as inlet and outlet respectively for the crank case oil, and ports in its top comprising respectively vapor inlet and outlet ports. A pipe or conduit 16 connects the inlet port 17 of the heating element 15 to a pump conventionally illustrated at 18, which is located at the bottom of the crank case, and is adapted to be operated from the crank shaft. A pipe or conduit 19 connects the outlet port 20 with the end of the crank case 10 and preferably has its orifice at a higher level than the inlet to the pump. Intermediate the ends of this conduit 19 is a cooling chamber 21, which, as shown, is substantially cylindrical, and is provided with heat radiating fins. This chamber serves to slow up the passage of the oil from the heating element 15 back to the crank case, and to hold it a sufficient length of time to cool it. The oil returning to the crank case is thereby "air cooled", but arrangements may be made for cooling it in some other manner, as by water cooling, if desired.
- Close to the inlet end of the chamber 15 is located a partition 22 having a port therethrough provided with a valve seat 23. The oil in passing from the inlet to the outlet must pass through this port, and a valve 24 secured to the end of a long spindle or valve stem 25 extending from the opposite end of the chamber 15, controls the passage of oil through this port and hence its rate of flow through the chamber 15. The spindle or valve stem 25 is composed of a metal which does not expand or contract when heated, and inasmuch as the exhaust manifold is constructed of expandable metal, it will be seen that as the latter heats up, the valve will open, and as it cools the valve will tend to close. The valve stem is screw threaded at 26, through the plug 27 in the end of the chamber 15, whereby the valve 24 may be easily adjusted relatively to the seat 23, in accordance with working conditions.
- The vapor outlet port 28 is connected by means of a pipe or conduit 29 to the auxiliary air inlet 14 of the carburetor, in which a slight vacuum is always present. Although the vacuum is in some instances so

slight as to be hardly measurable, it provides a sufficient continuous suction for withdrawing the gasoline and water vapors driven off from the oil in the heating element 15. The vapor inlet port 30 may be merely an air port if desired, through which air may enter to replace the vapors withdrawn through pipe 29, but I preferably connect this inlet port, by means of a pipe 10 or conduit 31 with the upper portion of the crank case 10, above the level of the lubricating oil therein.

It will be obvious that the pump 18 should be of a type which will not be injured by 15 back pressure, or should be provided with a safety device, which will prevent excessive pressure being generated on the pressure side of the pump when the engine is cold on starting and the valve 24 is closed, or 20 nearly closed. As the engine heats up the exhaust manifold expands, while the valve stem 25 does not, thus causing valve 24 to leave its seat 23 and open more and more the oil port in the partition 22. As this oil 25 port opens the pump 18, which, of course, tends to supply oil at a rate proportional to the speed of the engine, forces increasing amounts of oil through the heating chamber 15 in a given time.

30 As the lubricating oil passes through the heating chamber its temperature is raised to a degree above the boiling point of water, but preferably below 250° above which temperature many oils are liable to be injured, 35 and the water and gasolene are vaporized. The vapors are continually withdrawn from the chamber and conducted to the carburetor, from where they pass to the cylinders. The thermostatic control of the rate of flow 40 through the heating chamber is provided for the purpose of keeping the oil within the limit of temperature selected, it being obvious that a rapid flow should be permitted when the exhaust manifold is hot and 45 that the flow should be slow when the manifold is cool, in order that the proper distilling effect be realized.

It will be apparent to those skilled in the art that numerous arrangements of the piping and other features of the invention may 50 be used and I do not, therefore, limit myself to the exact form described and illustrated, but desire it to be understood that the invention may be embodied in numerous 55 alternative constructions.

Having thus described the invention what is claimed as new and desired to be secured by Letters Patent is:

1. The combination with an internal combustion engine having a reservoir for the lubricating oil, of means for removing the volatile impurities in the oil by distillation, 60 said means including an oil heating element, a conduit for conducting the oil from the reservoir to the heating element, a con-

duit for returning the oil to the reservoir, and automatic regulating means responsive to change in temperature of the heating element for controlling the flow of oil through the heating element.

2. The combination with an internal combustion engine having a reservoir for collecting the lubricating oil, of means for removing the volatile impurities in the oil by distillation, said means including an oil 70 heating element, a conduit for conducting the oil from the reservoir to the heating element, a conduit for returning the oil to the reservoir, and thermostatic means responsive to changes in temperature of the heating 75 element for automatically controlling the flow of oil into the heating element.

3. The combination with an internal combustion engine having a reservoir for the lubricating oil, of means for removing the volatile impurities in the oil by distillation, 80 said means including an oil heating element, a conduit for conducting the oil from the reservoir to the heating element, a conduit for returning the oil to the reservoir, a valve 85 controlling the flow of oil through the heating element, and thermostatic means for moving the valve, said means being responsive to change in temperature of the heating 90 element.

4. The combination with an internal combustion engine having a reservoir for the lubricating oil, of means for removing the volatile impurities in the oil by distillation, 100 said means including an oil heating element mounted upon the exhaust pipe and having an oil port therein, a conduit for conducting oil from the reservoir to the heating element, a conduit for returning the oil to the reservoir, a valve for controlling the flow of 105 oil through the oil port and thermostatic means for determining the extent of valve opening for the purpose set forth, said means being responsive to change in temperature of the heating element.

5. The combination with an internal combustion engine having a reservoir for the lubricating oil, of means for removing the volatile impurities in the oil by distillation, 110 said means including an oil heating element, a conduit for conducting the oil from the reservoir to the heating element, a pump for forcing oil through said conduit, a conduit for returning the oil to the reservoir, means for cooling the oil passing from the 115 heating element to the reservoir, and thermostatic means for regulating the flow of oil through the heating element, said last mentioned means being responsive to changes in temperature of said heating element.

6. A purifier for the lubricating oil of an internal combustion engine consisting of a heating chamber having a volatile gas outlet, means for heating said chamber, means to cause lubricant to flow from said engine 120

to said heating chamber, and a thermostat for controlling the flow of lubricant into said heating chamber.

7. A purifier for the lubricating oil of an internal combustion engine consisting of a heating chamber having a volatile gas outlet, means for heating said chamber, means to cause lubricant to flow from said

engine to said heating chamber, a thermostat for controlling the flow of lubricant into said heating chamber, and means to cool said heated lubricant and return said cooled lubricant to the engine.

In testimony whereof I affix my signature.

THOMAS J. LITTLE, JR.
